ULTRA HIGH FREQUENCY RADIO RECEIVER

Wendell L. Carlson, Haddonfield, N. J., assignor
to Radio Corporation of America, a corpora-
tion of Delaware

Application March 31, 1938, Serial No. 199,199

9 Claims. (Cl. 250—20)

The present invention relates to ultra high frequency radio receivers, and has for its object to provide an improved tuning system for ultra high frequency receivers which includes an intermediate frequency amplifier tunable to a plurality of differing frequencies within a predetermined wave band, having a predetermined relation to the wave band response within which the receiver is operable.

10 It is also an object of the present invention to provide an intermediate frequency amplifier for an ultra high frequency receiver, which is tunable to a plurality of differing intermediate frequencies within a predetermined wave band and to provide the sole selective variable tuning means for the receiving system.

15 It is a still further object of the present invention to provide an intermediate frequency amplifier for ultra high frequency radio receiving systems which is responsive to a plurality of intermediate frequencies, and an improved interstage coupling and tuning means therefor.

20 The invention will, however, be better understood from the following description, when considered in connection with the accompanying drawings, and its scope will be pointed out in the appended claims.

In the drawings,

25 Figure 1 is a schematic circuit diagram of an intermediate frequency amplifier for an ultra high frequency superheterodyne receiver, embodying the invention, and

30 Figure 2 is a series of curves illustrating certain of the frequency response characteristics 35 of the amplifier shown in Fig. 1.

Referring to Fig. 1, the intermediate frequency amplifier comprises a series of cascade connected intermediate frequency amplifier electric discharge devices or tubes 5, 6, 7 and 8 and tuned 40 coupling transformers 9, 10, 11 and 12, the last being coupled to the second detector 13.

45 The primaries 14 and the secondaries 15 of the successive coupling transformers are tunable by means of shunt capacitors 16 to a predetermined intermediate frequency which is a low percentage or a sub-multiple of the highest signal frequency to be received, such as 10.5 megacycles, for example, which is preferably substantially ten percent of the highest frequency with 50 in which the receiving system is responsive. In the present example, the receiving system may be considered to have a response range of from 105 down to 100 megacycles.

55 The signal receiving means or input tuning system and oscillator for the superheterodyne re-

ceiver are indicated at 17 and the tube 5 may be considered as the first detector or mixed tube which receives signals on a grid 18 and oscillations from local generator on the grid 19. The r-f tuning system is broadly tuned for response within the range of from 100 to 105 megacycles without manual tuning and any signals within that range are applied to the second detector 5 to combine with the locally generated oscillations to produce an intermediate frequency within the range of from 10 to 10.5 megacycles. The local generator or oscillator is preferably crystal controlled or otherwise arranged to give high stability, that is, the same order of stability as present on the received signal carrier frequency.

5 In order to select ultra high frequency signals, it has been found to be most dependable and accurate to provide adjustable tuning at low frequencies, after heterodyne detection, with fixed tuned r-f and local oscillator circuits. Accordingly, the intermediate frequency amplifier is caused to be adjustably tunable within the lower frequency range in a series of steps, for example, in five steps, as indicated in Fig. 2, for a relatively sharp response about mean frequencies at 10.0, 10.125, 10.25, 10.375 and 10.5 megacycles. A greater or lesser number of tuning adjustment points may be arranged in the amplifier to cover a greater or lesser number of receivable signal channels within the response range of the receiving system as may be desirable. The five pre-selection points of tuning and the frequency range referred to are shown, only by way of example, as being one of several present preferred tuning points in a predetermined high frequency 25 tuning range.

30 The primaries and secondaries 14 and 15 of the interstage coupling transformers are further tunable to an initial adjustment by movable magnetite cores indicated at 20 and 21, each associated with one of the windings for varying the inductance thereof. The interstage coupling means are further tunable to the successive lower frequency response bands about the selected mean frequencies by adding fixed inductances 23 40 to 26, inclusive, in pairs to the primary and secondary circuits in connection with the low side of the primary and secondary windings 14 and 15.

45 This is accomplished by movable tap switch 50 connections 27 in the secondary circuit and 28 in the primary circuit, in connection with taps 29 to 33, inclusive, along the series connected coils 23 to 26, inclusive, to progressively include an additional coil in the primary and in the sec- 55

ondary circuit with each succeeding adjustment from the taps 29 toward the taps 33.

The mutual coupling between the primary and secondary is increased as additional inductance is included in the two circuits, by the presence of coupling capacitors 34 connecting the low sides of the main primary and secondary windings 14 and 15.

The coupling capacitors 34 are permanently connected between the low potential sides of the main primary and secondary windings or between the initial primary and secondary switching taps, as shown, and serve to increase the coupling between the primary and secondary circuits for each interstage coupling transformer as the taps 27 and 28 are moved progressively to include additional inductance in each circuit.

This circuit arrangement provides a primary circuit and a secondary circuit, in this case an output anode circuit and an input grid circuit, 20 for each intermediate frequency amplifier stage, comprising the primary and secondary of a coupling transformer, the windings of which are tunable by means of movable magnetite or ferromagnetic cores and by shunt capacitors.

In addition, the low potential ends of each primary and secondary are connected with additional coupling windings in pairs, the windings for the primary and secondary being in series 30 and having a switch connection for including the shunt tuning capacitor in parallel with additional coupling windings in each circuit.

A coupling capacitor connected with the low potential ends of the primary and secondary provides increasing coupling as the inductance in each circuit is increased, maintaining a relatively high gain throughout the tuning range and holding up the gain at the low frequency end of the range appreciably. This is shown in Fig. 2 35 in the curves 35-39, inclusive, which represent the response characteristic of each stage coupling means for the successive tuning adjustments from 10.5 megacycles to 10.0 megacycles as additional coupling is included in the coupling circuits. The coupling capacitors tend to hold the coupling in the primary and secondary circuits substantially constant.

The selector switches 27 and 28 are preferably connected for uni-control or gang operation, as 50 indicated by the dotted connection 40, so that they move progressively from tap to tap over the five positions provided in the circuit of the present example.

The anode current and grid bias potentials are 55 preferably supplied through connection leads indicated at 41 and 42 to the tap switches 27 and 28, suitable filter means being provided as indicated by the series resistors 43 and the filter capacitors 44 for each circuit.

In an amplifier of this type it has been found 60 preferable to provide a separate channel amplifier and rectifier for the supply of automatic volume control potentials. This amplifier channel is tunable for broad response throughout the tuning range of the main amplifier channel which, in this case, is from 10 to 10.5 megacycles.

Such a separate channel amplifier is indicated 65 by the amplifier tube 45 in which is combined a diode rectifier 46 providing the a. v. c. potentials.

In the present arrangement, the secondary for 70 the third i-f amplifier tube 8 is tapped, as indicated at 47, for supplying signals to the amplifier tube 8, while the entire secondary voltage is taken through the connection lead 49 and applied to the control grid 50 of the a. v. c. am-

plifier 45. The output of the amplifier is coupled through a broadly tuned coupling transformer 51 with the a. v. c. diode rectifier anode 56 which has a cathode 52 in common with the amplifier in the same envelope. The cathode circuit is completed through ground and a diode output resistor 53 in series with the secondary 54 of the transformer 51. An intermediate frequency by-pass capacitor 55 is provided for the resistor 53 and a. v. c. potentials are derived 10 from the resistor through output leads 56.

It will be noted that the primary and secondary of the transformer 51 in the a. v. c. amplifier channel are tuned broadly without shunt capacitors, and the tuning response is further broadened by the use of a shunt resistor indicated at 15 57.

The main signal amplifying channel of the intermediate frequency amplifier is made substantially sharply responsive to a plurality of 20 signal bands of relatively narrow range about mean intermediate frequencies corresponding to desired signal channels or broadcasting stations, while the separate channel a. v. c. amplifier is coupled into the amplifier at a suitable point 25 following the initial amplifier stages, to respond broadly to signals in any of the selected bands, whereby a. v. c. potentials may be applied to the receiving system effectively for each of the signal receiving tuning adjustments.

Furthermore, by connecting the a. v. c. channel, as shown, amplification of the received signals for automatic volume control purposes is obtained while at the same time the selective tuning of the a. v. c. supply circuit and the additional means which would be required for that purpose is eliminated.

The second detector 13 is likewise a diode rectifier as indicated at 58, having an output resistor 59 to which is connected the control grid 60 of an amplifier included in the same envelope with the diode and having a common cathode 61 therewith. Rectified signals derived from the diode output resistor 59 are amplified by the 40 amplifier 60 and derived therefrom from an output anode indicated at 62 and an audio frequency output circuit 63. The receiving system may include further audio frequency amplifying apparatus, not shown.

In a practical embodiment of the tuning system, the switches 27 and 28 and the associated contacts 29 to 33 inclusive are provided by rotary tap switches preferably of the well-known ganged multiple section type at present used for wave band change control in receiving systems, 65 and the coupling windings 23 to 26, inclusive, are mounted directly between the switch contacts substantially as indicated in the drawings, Fig. 1. This simplifies the circuit connections for the windings and reduces the length of connection 60 leads required for the series-connected coil system, since the switch contacts become, in effect, the coil terminals.

The intermediate frequency amplifier is tunable at a lower frequency than the frequency of 65 the signals to be received and each of the tuning steps is arranged to be a small percentage of the frequency of the signal frequency being received. With this arrangement, the tuning system for the receiver and the oscillator may be 70 fixed tuned for broad response in an ultra-high frequency band, such that the receiver may be tuned within that band at the relatively low intermediate frequency with a high degree of stability of operation, since none of the ultra-high 75

frequency tuning circuits are disturbed or changed by the tuning operation.

In the present example, a tuning range of from 100 to 105 megacycles is obtainable with stable operation, and the tuning range of the intermediate frequency amplifier may be a relatively narrow range of from 10 to 10.5 megacycles. While five tuning points have been shown in the present system, it should be appreciated that more or less may be provided for the same or wider over-all tuning range, as may be desired. The intermediate frequency amplifier is operable at a relatively low percentage of the frequency range within which signals are to be received and the system is particularly adapted for tuning in signal receiving ranges above 100 megacycles.

I claim as my invention:

1. The combination with a signal receiving system of an intermediate frequency amplifier comprising a plurality of amplifier stages, an amplifier tube and interstage coupling means therefor in each stage, said coupling means comprising a coupling transformer having a primary winding, a secondary winding, a coupling capacitor connected between the low potential ends of said windings, a shunt tuning capacitor for each of said windings, additional coupling windings for said primary and secondary connected in series therewith at the low potential ends thereof, and selective switching means for progressively including said additional coupling windings in circuit with said primary and secondary and said shunt tuning capacitors to tune said amplifier progressively in a series of steps within a predetermined frequency range.

2. In an ultra high frequency superheterodyne receiver, an intermediate frequency amplifier comprising a plurality of amplifier stages, an amplifier tube and interstage coupling means therefor in each stage, said coupling means comprising a coupling transformer having a primary winding, a secondary winding, a coupling capacitor connected between the low potential ends of said windings, a shunt tuning capacitor for each of said windings, additional coupling windings for said primary and secondary connected in series therewith at the low potential ends thereof, and selective switching means for progressively including said additional coupling windings in circuit with said primary and secondary and said shunt tuning capacitors to tune said amplifier progressively in a series of steps within a predetermined low frequency range, and means providing broad fixed tuning response for said receiver preceding said intermediate frequency amplifier, in an ultra high frequency range having a predetermined relation to said low frequency range whereby said intermediate frequency amplifier provides a signal selecting means for said receiver at mean frequencies corresponding to desired signal frequencies and at a fixed relatively low percentage of said signal frequencies.

3. The combination with a tuning system for an ultra high frequency radio signal receiver, of an intermediate frequency amplifier comprising a plurality of cascade connected amplifier tubes, means for tuning said amplifier in a plurality of spaced relatively narrow pass bands, comprising an interstage coupling transformer having a primary and a secondary, an anode circuit connected with the primary at the high potential side thereof, an input grid circuit connected with the high potential side of said secondary winding, a plurality of coupling windings connected in se-

ries with said primary and secondary and coupled in pairs, and means for progressively including said additional windings in circuit with said primary and secondary for tuning said amplifier to a plurality of differing submultiple frequencies of desired signal frequencies.

4. The combination with a tuning system for an ultra high frequency radio signal receiver, of an intermediate frequency amplifier comprising a plurality of cascade connected amplifier tubes, means for tuning said amplifier in a plurality of spaced relatively narrow pass bands, comprising an interstage coupling transformer having a primary and a secondary, an anode circuit connected with the primary at the high potential side thereof, an input grid circuit connected with the high potential side of said secondary winding, a plurality of coupling windings connected in series with said primary and secondary and coupled in pairs, and means for progressively including said additional windings in circuit with said primary and secondary for tuning said amplifier to a plurality of differing submultiple frequencies of desired signal frequencies, said primaries and secondaries being provided with movable tuning cores and said last named means including switch elements having contacts providing terminal connections for said additional windings.

5. In an ultra-high frequency radio signal receiving system, the combination of signal receiving means broadly responsive to a band of signal frequencies, an intermediate frequency amplifier including a plurality of amplifier tubes and interstage coupling means therefor, a first detector coupling said signal receiving means and said intermediate frequency amplifier, said interstage coupling means providing the sole tuning means for said receiving system and being tunable conjointly to a plurality of differing intermediate frequencies, each of which is a low percentage of a selected frequency in the tuning range of said receiver, and said interstage coupling means each comprising a coupling transformer having a primary winding, a secondary winding, a coupling capacitor connected between the low potential ends of said windings, a shunt tuning capacitor for each of said windings, and additional coupling windings for said primaries and secondaries connected in series therewith at the low potential ends thereof, and selective switching means for progressively including said additional coupling windings in the circuit with said primary and secondary and said shunt tuning capacitors to tune said amplifier progressively in a series of steps within a predetermined frequency range which is a small percentage of the frequency range to which said receiving system is responsive.

6. In an ultra-high frequency radio signal receiving system, the combination of signal receiving means broadly responsive to a band of signal frequencies, an intermediate frequency amplifier including a plurality of amplifier tubes and interstage coupling means therefor, a first detector coupling said signal receiving means and said intermediate frequency amplifier, said interstage coupling means providing the sole tuning means for said receiving system and being tunable conjointly to a plurality of differing intermediate frequencies, each of which is a low percentage of a selected frequency in the tuning range of said receiver, means providing automatic volume control potentials for said receiving system coupled to an intermediate interstage coup-

ling means in said amplifier and comprising an amplifier tube, a rectifier, an output circuit for said rectifier, and coupling means between said amplifier and rectifier broadly responsive to signals within the tuning range of said intermediate frequency amplifier, whereby said automatic volume control means is effective for all tuning adjustments of said receiving system.

7. In a superheterodyne receiver for ultra-high frequency signals, the combination of a fixed tuned signal receiving system including an oscillator and first detector broadly responsive to signals within a predetermined frequency range, an intermediate frequency amplifier coupled to said first detector, means for tuning said intermediate frequency amplifier through a low frequency range which is a small percentage of the tuning response range of said receiving system, said tuning means comprising interstage coupling transformers for said amplifier having primary and secondary windings tuned to a mean frequency response in a relatively narrow pass band which mean frequency is a small percentage of the highest frequency to be received in the tuning range of the receiver, additional coupling windings for said primaries and secondaries in series therewith at the low potential ends thereof, and selective switching means for progressively including said additional coupling windings in circuit with said primaries and secondaries to tune said amplifier progressively in a series of steps at lower frequencies within the predetermined frequency range of the amplifier.

8. In a superheterodyne receiver, a system for tuning said receiver in a relatively narrow frequency range above 100 megacycles, comprising tuning, oscillator and first detector means broadly responsive to signals in a frequency band of the order of 5 megacycles in width in said predetermined high frequency range to provide a predetermined intermediate frequency in a lower and narrower frequency range at frequencies

substantially ten per cent of the frequencies in said signal receiving range, an intermediate frequency amplifier coupled to said first detector means, said amplifier having interstage coupling means conjointly tunable in predetermined steps to a plurality of differing frequencies within said low frequency range as the sole tuning control means for said receiver.

9. In a superheterodyne receiver, a system for tuning said receiver in a relatively narrow frequency range above 100 megacycles, comprising tuning, oscillator and first detector means broadly responsive to signals in said predetermined high frequency range to provide a predetermined intermediate frequency in a lower and narrower frequency range at frequencies substantially ten per cent of the frequencies in said signal receiving range, an intermediate frequency amplifier coupled to said first detector means, said amplifier having interstage coupling means conjointly tunable to a plurality of differing frequencies within said low frequency range as the sole tuning control means for said receiver, said intermediate frequency amplifier having interstage coupling transformers provided with movable magnetite cores and shunt tuning capacitors for tuning said transformers to the highest frequency in the low frequency tuning range, a capacitor providing coupling between the low potential ends of the primary and secondary windings of said transformers, additional coupling windings connected in circuit with said primary and secondary windings at the low potential ends thereof, and multiple contact gang-controlled switch means for connecting said additional coupling windings progressively in circuit with said primary and secondary windings and said shunt tuning capacitors to tune said amplifier progressively to lower frequencies within said low frequency tuning range, said coupling windings being connected between the contacts of said switching means.

WENDELL L. CARLSON.
